UNITED STATES PATENT OFFICE.

THEODORE FREELINGHUYSEN EMANS, OF MENDON, OHIO.

CLOD CRUSHER AND PULVERIZER.

SPECIFICATION forming part of Letters Patent No. 339,391, dated April 6, 1886.

Application filed January 13, 1886. Serial No. 188,392. (No model.)

To all whom it may concern:

Be it known that I, THEODORE FREELING-HUYSEN EMANS, a citizen of the United States, and a resident of Mendon, in the county of Mercer and State of Ohio, have invented certain new and useful Improvements in Clod Crushers and Pulverizers; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved clod crusher and pulverizer. Fig. 2 is a vertical axial section of the same. Fig. 3 is a vertical section on line $x-x$, Fig. 2. Fig. 4 is a perspective detail view of the adjustable seat and foot-rest, and Fig. 5 is a similar view 20 of one of the cutters.

Similar letters of reference indicate corresponding parts in all the figures.

My invention has relation to that class of clod crushers and pulverizers in which a number of cutters are pivoted with their ends in wheels mounted upon an axle, the wheels and cutters forming cylinders, which are journaled similarly to a land-roller; and it consists in the improved construction and combination of 30 parts of the same, as hereinafter more fully described and claimed.

In the accompanying drawings, the letter A indicates a rectangular frame having the tongue B projecting through its middle and projecting forward, the inner end of the tongue dividing the frame. A nutted bolt, C, passes through a perforation, D, in the rear end of the tongue, and has a slotted and flanged plate, E, sliding upon its upper end, the said plate having downwardly-projecting flanges F F at the forward ends of its side edges, while the remaining portions of the side edges of the plate are formed with upwardly-projecting flanges G G, the downwardly-projecting flanges 40 fitting upon the sides of the tongue and retaining the plate in its proper position upon the upper side of the tongue. The rear end of this plate is provided with a cross-head, H, which forms a foot-rest, and the seat I for the driver 50 is secured upon a spring-support, J, which has its lower end bent rearward and formed with

a longitudinal slot, K, which fits upon the nutted bolt, the said rearwardly-bent end fitting between the upwardly-projecting flanges at the sides of the slotted plate. A bolt or axle, 55 L, passes through the frame, fitting with its ends in the side pieces of the frame, and two pairs of wheels, M M, are journaled upon this axle—one pair at each side of the inner end of the tongue. These wheels are secured together 60 by means of bolts N, the screw-threaded ends of which pass through the spokes of a pair of wheels, and are provided with nuts O upon the inner and outer sides of the wheels, which nuts clamp the wheels upon the ends of the 65 bolts. The rims of these wheels are provided with a number of transverse perforations, P, into which the journals or trunnions Q of the cutters R are pivoted, the said cutters having their sharp edges projecting to one side of the 70 journals. The inner edges of these cutters, which are flush with the journals, are provided each with an obliquely-projecting cog or arm, S, and the free ends of these arms may bear against the rear side of the inner portions 75 of the adjoining cutters and against the inner or rear faces of each other, so as to force a number of the cutters to stand at the same angle to the periphery of the wheels when one cutter is tilted to this angle.

The cutters all fold or tilt to one side, and it will be seen that when the implement is drawn in one direction, so that the cutters will have their sharp edges pointing downward upon the forward sides of the cylinders, the 85 said cutters will cut and break all the clods which they may encounter upon the ground, the sharp edges coming directly down upon the clods, while by reversing the cylinders upon the axle, which may easily be done by removing the axle and raising and reversing the frame, the flat sides of the cutters will strike the ground, causing the cylinders to act as common rollers.

The lateral play of the cutters between the 95 wheels may be adjusted by adjusting the wheels upon the rods by means of the nuts, and the wheels may be separated sufficiently to remove the cutters or to insert cutters by means of the nuts being unscrewed from the 100 rods.

The seat may be adjusted so as to cause the

weight of the driver to counterbalance the weight of the tongue and to remove this weight from the neck-yoke and from the necks of the draft-animals, and the foot-rest may be adjusted with the seat and independent of the seat, allowing it to be adjusted closer to and farther from the seat according to the length of the legs of the driver.

The downwardly projecting side flanges of the foot-rest plate guide the said plate upon the rear end of the tongue, and the upwardly-projecting flanges upon the same plate guide the rearwardly-bent slotted end of the seat-support.

15 Having thus described my invention, I claim and desire to secure by Letters Patent of the United States—

1. In a clod-crusher and soil-pulverizer, the combination of wheels having transversely-perforated rims, and suitably journaled in a frame, with cutters having journals or trunnions fitting in the perforations of the wheels projecting from the ends of their inner edges, and having obliquely-projecting arms upon 20 the said inner edges, as and for the purpose shown and set forth.

2. In a clod-crusher and soil-pulverizer, the combination of a frame having a tongue projecting from it and dividing it in two halves 30 by its rear end, an axle fitting in transverse perforations in the side pieces of the frame and through the rear portion of the tongue, wheels having their rims transversely perforated and journaled in pairs upon the axle, 35 being secured at their proper distance from

each other by means of nutted bolts passing through the spokes of the wheels and bearing upon both sides of the spokes with the nuts, and cutters having journals projecting from the ends of the inner edges, fitting in the perforations in the wheels, and having obliquely-projecting arms projecting from their inner edges, as and for the purpose shown and set forth. 40

3. In a clod-crusher and soil-pulverizer, the combination of a frame having the rear end of the tongue dividing it and formed with a vertical perforation at the rear end, a plate having a foot-rest at its rear end, and having a longitudinal slot and upwardly-projecting flanges at its side edges, and downwardly-projecting guide-flanges at the forward ends, of its side edges clamping the sides of the rear end of the tongue, a seat support having its lower end bent rearward and slotted longitudinally, fitting between the upwardly-projecting flanges of the foot-rest plate, and a nutted bolt fitting into the perforation of the tongue and having its upper headed end securing the slotted end of the seat-support and the slotted foot-rest plate, as and for the purpose shown and set forth. 55

In testimony that I claim the foregoing as my own I have hereunto affixed my signature in presence of two witnesses.

THEODORE FREELINGHUYSEN EMANS.
